UNITED STATES PATENT OFFICE.

ALFRED M. MARSHALL, OF SAVANNAH, GEORGIA.

MIXING AND SCREENING DEVICE FOR FERTILIZERS AND THE LIKE.

1,392,589.

Specification of Letters Patent.

Patented Oct. 4, 1921.

Application filed January 25, 1921. Serial No. 439,769.

To all whom it may concern:

Be it known that I, ALFRED M. MARSHALL, a citizen of the United States, residing at Savannah, in the county of Chatham and 5 State of Georgia, have invented certain new and useful Improvements in Mixing and Screening Devices for Fertilizers and the like, of which the following is a specification.

10 This invention relates to mixing and screening devices for fertilizers and the like and it comprises a receptacle having a shaft with a plurality of stirrers or paddles therein, advantageously arranged to mix contained material and tend to throw it toward 15 the center and bottom of the receptacle, in combination with a sub-receptacle in proximity to the first receptacle such sub-receptacle arranged to receive mixed material 20 from the main receptacle and having means for screening said mixed material; all as more fully hereinafter set forth and as claimed.

One object of the present invention is the 25 provision of a simple and relatively inexpensive mixing and screening means which can be used by a farmer for the purpose of mixing fertilizers and the like. It frequently happens that the farmer does not 30 desire to use mixed fertilizers of the character manufactured, but on the other hand, desires to mix his own fertilizers at the farm, and to use more or less of a certain ingredient as the character of his particular soil 35 may require. Frequently a farmer desires to mix the fertilizer with a proportion of earth before spreading it on his soil. For these and other reasons a simple and economical form of fertilizer mixing and 40 screening apparatus is desideratum on the farm.

In the present invention I have devised a relatively inexpensive and simple mixing and screening apparatus, of which the following 45 is a detailed description, reference being had to the accompanying drawing.

In the drawings, Figure 1 is a vertical section through the machine, certain parts being shown in elevation; and

50 Fig. 2 is an end elevation;

Fig. 3 is a vertical section along line 3—3 of Fig. 1 and

Fig. 4 is a bottom plan view of the screen.

Fig. 5 is a detail of the screen tapping 55 means.

Referring to the drawings in which the

same references designate corresponding parts in the several views, 1 indicates a receptacle such as a barrel or the like provided with a feeding hopper 2 placed over 60 the opening 3. The feeding hopper is provided with a stationary screen 4 and a slideable screen 5. By this arrangement the openings of the screen 4 may be diminished in size by the use of the screen 5 and the 65 feeding of large pieces of foreign matter into the receptacle 1 may be prevented. The barrel or receptacle 1 is supported on standards 6 each of which is provided with a bearing 7 for reception of the shaft 8. The 70 shaft is provided at one end with a driven sprocket 9 operated by means of chain 10 driven from the sprocket gear 11 which is keyed to a shaft 12 carrying the pulley 13 operated by a belt 14 from a source of power 75 not shown. The shaft 8 is provided with a plurality of slotted plates 15 preferably bolted to the shaft and carrying peculiarly shaped paddles, stirrers or propeller-blades 16 secured to the plates in any desired manner. I usually provide 6 to 8 of these propeller blades but a greater or less number may be used as the exigencies of any particular case demand. These propeller blades 80 are preferably curved in the direction of rotation of the shaft and are twisted toward the center of the machine in order that they may tend, while stirring and mixing the contents of the barrel, to throw it toward the center and the bottom. The shaft is also 85 advantageously provided with a centrally located stirring arm 17 which may be secured to the shaft in a hole therein and locked in position by lock nuts 18. This stirring arm is primarily for the purpose of preventing 90 accumulations and piling up of material 95 over the bottom opening of the barrel.

The material mixed in the barrel or receptacle 1 is discharged through opening 19 into the screening receptacle to be described. 100 This opening 19 is provided with a removable cover 20 which may slide longitudinally of the barrel.

In the opening at the bottom of the barrel is a small plate 21 held in place by the spider 105 arms 22, this plate serving to prevent dumping or falling of the material directly upon the gears and gear casing to be described.

The screen basket 23 is located directly under the opening of the barrel and is supported by the shaft 24 which is journaled in the bearing 25 held in position by means of 110

the arm 26. This shaft carries beveled gear 27 meshing with beveled gear 28, both of which are inclosed in the casing 29 and beveled gear 28 is driven by shaft 30 (supported in hanger 31) having the sprocket 32, driving chain 33 engaging the sprocket 34 loosely mounted upon the shaft 8. Through the clutch mechanism 35 operated by hand lever 35', (Fig. 2) the sprocket 34 may be 10 rotated and the shafts 30 and 24 driven to rotate the basket screen 23. Depending from the barrel and surrounding the opening is the chute or pipe-like device 36 terminating at about the top of the basket. This 15 chute may be provided with door 37 for the purpose of inspecting the interior of the apparatus during operation (Fig. 3). The screen basket is supported by means of the stirrups 38 attached to the barrel, the stirrups carrying a bearing 39 for the bottom of the shaft 24. Attached to the bottom of the stirrups and about half way up the basket screen is a hood or funnel member 40 preferably flared at its extremity as at 41 20 and carrying a loosely mounted hoop 42. This is for the purpose of attaching a sack 43 in position, the sack being placed over the flared end 41 and the hoop being brought down over the outside of the sack to hold it 25 in position over the flared end. The arm 26 carries two or more stationary blades 26', the lower ends of which extend into the screen basket close to the walls and the bottom thereof. The rotation of the screen 30 with respect to these paddle blades insures the thorough screening of the material.

The screen rotates with respect to the stirrups 38. The screen is advantageously reinforced by means of cross braces and encircling braces 44.

When the material being screened is of a consistency which would cause it to stick to the screen, the tapping device 45 may be used. This may consist of a small piece of 45 weighted steel hinged to the stirrer 38 with one end resting on the upper ring 44 of the screen. This upper ring may be roughened slightly with a result that when the screen revolves with respect to this tapping device 50 the screen will be shaken slightly and this shaking will serve to prevent the material adhering to the wall of the screen.

In operation of the device just described, the material to be mixed and screened is 55 dumped into the barrel. It may be of any size. For the sake of illustration I may charge 100 pounds of acid phosphate, 50 pounds of cottonseed meal and 50 pounds of potash ingredient to be used in mixing the 60 fertilizer. The paddle blades or propellers are then set in action through operation of the pulley 13, sprocket 11, sprocket 9 and shaft 8 causing a thorough mixing and tumbling action inside of the barrel with a tendency for the stirrers to lift the material and

dump it toward the bottom and the center of the barrel. While the shaft is still operating the clutch 35 is thrown into engagement with the sprocket 34 causing rotation of shaft 30 and shaft 24 carrying the basket 70 screen 23. Then the door 20 at the bottom of the barrel is opened permitting dumping of the contents of the barrel into the screen, it being guided to the inner periphery of the screen by the hood 36. I prefer to run the 75 screen at a slightly greater rate than the shaft in the barrel. From 30 to 60 revolutions per minute for the operation of the shaft and from 40 to 70 revolutions per minute for the operation of the screen have 80 proved very satisfactory. As the barrel empties and the material is delivered to the screen any remaining lumps from the barrel are broken up by the screen and the material is screened and further thoroughly mixed. 85 Occasionally a small quantity of residue accumulates in the screen and this may be removed through the side door 37 of the hood. The paddles carried by the arm 26 are stationary and they serve to force the 90 material through the screen as it is fed thereto from the barrel. The material screened is delivered to the sack which is held in position in the manner described.

What I claim is:—

1. An apparatus for mixing and screening material such as fertilizer and the like, comprising a receptacle, a shaft therein, stirring arms on the shaft for mixing the material and means for feeding material to 100 and delivering material from said receptacle, in combination with a screening device located under the delivering means of the said receptacle and comprising a rotatable screen, and means for rotating the same on a vertical 105 axis while the stirring devices of said receptacle are in operation.

2. An apparatus for mixing and screening materials such as fertilizer and the like, comprising a main receptacle, stirring devices 110 therein for mixing the material, and means for feeding material to and delivering material from said main receptacle, in combination with a screening device located in proximity to the delivering means of the main receptacle comprising a rotatable screen, and means for operating the stirring device of the main receptacle and operating the screening device simultaneously and for operating the stirring device independently 115 of the screening device.

3. In an apparatus for mixing and screening fertilizing materials and the like a main receptacle, a shaft therein carrying a plurality of stirrer arms curved in the direction 125 of rotation of the shaft, means for rotating the shaft, an opening in said receptacle, a screening device located in proximity to said opening for receiving material which has been mixed in said receptacle by said arms, 130

and means connected with the shaft rotating mechanism for operating the screening mechanism.

4. An apparatus for mixing and screening 5 fertilizer and the like comprising a main receptacle having feeding means for the material to be mixed and delivering means for the mixed material, mixing means in the said receptacle mounted upon a shaft and driving 10 mechanism for said shaft in combination with screening mechanism located in proximity to the delivering means of the main receptacle and comprising a screen with means for rotating the same, the means for 15 rotating the said screen being arranged to be driven by the operating means for said shaft, and a clutch mechanism arranged for

engaging or disengaging the screen operating mechanism with the shaft operating mechanism.

20

5. An apparatus for mixing and screening fertilizer material, a main receptacle with mixing devices therein and having means for feeding material thereto and delivering material therefrom, in combination with a 25 screen located in proximity to the delivering means of the said receptacle, a chute leading from the delivering means of the said main receptacle to said screen, and means for rotating the screen and the mixing device of 30 said receptacle simultaneously.

In testimony whereof I have hereunto affixed my signature.

ALFRED M. MARSHALL.
